[57] CLAIM

The ornamental design for a furniture element, as shown and described.

DESCRIPTION

FIG. 1 is a front perspective view of my new furniture element looking down from the top at the right side;

FIG. 2 is a front elevational view of the furniture element of FIG. 1;

FIG. 3 is a rear elevational view of the furniture element of FIG. 1;

FIG. 4 is a top plan view of the furniture element of FIG. 1; and,

FIG. 5 is a left side elevational view of the furniture element of FIG. 1.

The structure shown in broken lines is for illustration purposes only and forms no part of the claimed design.
